ATTORNEY

UNITED STATES PATENT OFFICE

THOMAS J. AYRES, OF LOS ANGELES, CALIFORNIA

STAGE CABLE CONNECTER

Application filed January 25, 1928. Serial No. 249,435.

My invention relates to cable connectors and more particularly to a type of connector suitable for stage wiring and the objects of my invention are: first, to provide a connector 5 of this type by means of which one or more circuits may be readily made or broken; second, to provide a device of this class which when closed is not easily accidentally disengaged; third, to provide a connector of 10 this class which will not be disengaged by accidental pulling or straining of the cables which are connected thereto; fourth, to provide a device of this class in which the portions carrying the live terminal is so constructed 15 that the latter cannot be accidentally short-circuited or brought into contact with the ground; fifth, to provide a device of this class which when in normal contact making engagement cannot be broken by longitudinal strain on the respective cable connections; sixth, to provide a device of this 20 class which is opened by a relative angular movement of the plug and receptacle member; seventh, to provide a device of this class 25 which is provided with spring catch means preventing accidental angular movement of the plug and receptacle members which would normally break the contact; eighth, to provide a device of this class in which a 30 wiping action takes place between the blade and drum contact members in making and breaking the contact thereof; ninth, to provide a device of this class in which relatively 35 large contact surfaces may be accommodated in a relatively small space; tenth, to provide a device of this class in which the cable ends are rigidly held from displacement by means of the cover concealing the terminal; and eleventh, to provide a device of this class 40 which is efficient, durable, economical of structure, easy to manipulate and which will not readily deteriorate or get out of order.

With these and other objects in view as will appear hereinafter my invention consists of 45 certain novel features of construction, combination and arrangement of parts and portions as will be hereinafter described in detail and particularly set forth in the appended claims, reference being had to the accompanying drawings and to the characters of

reference thereon which form a part of this application in which;

Figure 1 is a perspective view of the receptacle portion of my device; Fig. 2 is a perspective view of the plug portion of the device; Fig. 3 is a side view of the receptacle portion with parts and portions broken away and in section in order to facilitate the illustration; Fig. 4 is a sectional view thereof along the line 4—4 of Fig. 3 showing the contact and cable portions in elevation; Fig. 5 is a cross sectional view thereof along the line 5—5 of Fig. 3; Fig. 6 is a plan view of the plug member showing parts and portions thereof broken away and in section in order to facilitate the illustration; Fig. 7 is a sectional view of the plug member taken along the line 7—7 of Fig. 6 showing the contact blades and cable connection in elevation; Fig. 8 is a cross sectional view thereof taken along the line 8—8 of Fig. 6, and Fig. 9 is an elevational view of the connector assembled together showing by dotted lines the position taken by the plug member when the plug and receptacle are being connected.

Similar characters of reference refer to similar parts and portions throughout the several views of the drawings.

The receptacle member 1, plug member 2, contact jaws 3, contact blades 4, spring catch 5, covers 6 and 7, terminal screws 8 and 9, and cover screws 10 and 11 form the principal parts and portions of my device.

The receptacle member 1 consists of a substantially rectangular block of insulating material, the block being reduced to about one-half its normal thickness over one-half its length. The inner transverse wall 1b is tapered outwardly forming a substantially dove-tailed surface. Within the reduced portion 1a are provided parallel longitudinal spaced apart slots 1c which are adapted to accommodate the jaw contact members 3. The latter may be forced into the slot after the member 1 has been formed or they may be formed in place with the latter. The rear end of the receptacle member 1 is also reduced in thickness to provide space for the cover member 6, the upper surface of the insulating cover being substantially flush with the upper

surface of the plug member 1. A transversely disposed cavity 1e is provided in the portion 1d, the depth of this cavity being approximately equal to the depth of the slots 1c. A 5 rearwardly extending channel 1f is provided for accommodating the end of the cable to which the receptacle is to be connected. The cover member 6 is provided with a number of downwardly extending lateral serrations 10 6a which are positioned directly over the slot 1f. As illustrated in Fig. 4, the purpose of the serrations is to provide a binding means for securing the cable 12 thereby preventing any strain from being placed on the terminal 15 screws 8 and the electrical connections thereto. The jaw contact 3 is preferably made of resilient sheet metal such as brass and consists of a relatively long U-shaped portion 3a forming closely spaced contact jaws adapted 20 to fit snugly within the slot 1c and forming a receptacle therein for the reception of the knife blade 4 of the plug member 2. The upper surface of the contact jaw 3 is sunk slightly below the surface of the portion 1a 25 so that it is impossible to short circuit the contact 3 accidentally by bridging across with any conducting means. One arm of the U-shaped jaw contact is provided with a laterally disposed offset portion 3b extending 30 within the cavity 1e and provided with contact screws 8 which serve the purpose of connecting the electric conductors to the contact jaws 3.

In the preferred form illustrated, each receptacle 1 is provided with two spring contact jaws 3, although the invention is of course not limited to a double pole connector. The structure of the plug member 2 is insulating material and follows in general lines 35 40 that of the member 1. It is provided with a reduced portion 2a of substantially the same size of that of the reduced portion 1a. The end portion 2b of the reduced portion 2a is beveled in a manner corresponding to the 45 outline of the surface 1b of the receptacle 1 so that when in placing the members 1 and 2 together, end for end, and allowing the reduced portions 1a and 2a to overlap the beveled end portion 2b will register exactly with 50 the dovetailed portion 1b. Elongated contact blades 4 extend vertically in parallel spaced relation from the surface of the reduced portion 2a. The contact blades 4 are preferably molded in place and are prefera- 55 bly of angular form over the length of the contact blade portion. The portion 4a which forms the angle with the blade 4 is extended rearwardly, as shown best in Fig. 6, into the cavity 2c and a binding screw 9 is provided 60 at the end of the portion 4a within the cavity 2c. The cavity 2c is also provided with a rearwardly extending channel 2e for accom- 65 modating the cable 13, the conductors of which are connected to the blades 4 by means of the terminal screws 9. A cover member

7 identical with the cover member 6 previously described is provided for covering the cavity 2c and is also provided with serrations 7a extending laterally over the channel 2e and adapted to bind the cable 13 and prevent movement thereof. In the end of the reduced portion 1a of the member 1 is provided a spring catch 5 which is adapted to register with an indent 2d positioned in the wall portion 2g of the member 2. The upper corner 75 of said wall portion 2g is beveled in line with the indent 2d in order to facilitate the registering of the spring member 5 with indent 2d when connecting the members 1 and 2 together. It is of course understood that any other form of catch can be used in place of that shown in the illustration. The object of the catch is to prevent accidental dislocation of the members 1 and 2 when in connected position, the dovetailed joint performing 80 this function for the other abutting end of the members 1 and 2.

It will be noted that in making and breaking connections, the blades 4 describe an angular movement, resulting in a wiping action between the blades and the jaw contacts 3. This feature results in a clean contact surface being maintained and prevents corrosion and heating of the contact members.

The relatively long jaws and blades provide for ample contact surface which is also a very important feature of the device.

It is obvious from the construction as illustrated in the drawings and described in the foregoing specification that there is provided a device as aimed at and set forth in the objects of the invention and although I have shown and described a particular construction, combination and arrangement of parts and portions I do not wish to be limited to this particular construction, combination and arrangement but desire to include in the scope of my invention the construction, combination and arrangement substantially as 100 set forth in the appended claims.

Having thus described my invention, what I claim as new and desire to secure by Letters Patent is:

1. In a detachable cable connector, a substantially rectangular insulating block having a reduced portion extending from a line intermediate the ends of said block to one end thereof, a forwardly inclined ledge formed along said line, jaw contact members imbedded in said reduced portion of said block, a second insulating block having a like reduced portion, the outer end of said reduced portion of said second block being bevelled, blade contact members extending 115 upwardly from the surface of the reduced portion of said second block and adapted to register with said jaw contact members, said jaw contact members preventing lengthwise displacement of said blocks when in engage- 120 125 130

ment, and said inclined ledge adapted to dovetail with said bevelled end of said second block.

2. In a cable connector, a stepped receptacle member, jaw contact members imbedded in the upper face of the lower step portion of said receptacle member, a stepped plug member, blade contact members extending upwardly from the upper face of the lower step portion of said plug member adapted to connect with said jaw contact members, interlocking means on the end of said receptacle member and intermediate the ends of said plug member engageable on pivotal movement of said plug member around the end portion of the latter.

3. In a detachable cable connector, a pair of end on end disposed cutaway, rectangular insulating members the cutaway portions thereof overlapping, jaw contact members embedded in the contacting face of one of said members, blade contact members supported by the contacting portion of said other member and extending into said jaw contact members, the inner end portion of one of said members forming a dovetail joint with the abutting portion of said other member and a releasable catch means on the end of said former member adapted to engage said latter member and prevent accidental disengagement of said contacts.

In testimony whereof, I have hereunto set my hand at Los Angeles, California, this 11th day of January, 1928.
